United States Patent Office

Des. 226,694

Patented Apr. 10, 1973

226,694

NAIL CARE TOOL

Shogo Ishii, Tokyo, Japan, assignor to Syntak Company, Ltd.

Filed Nov. 1, 1971, Ser. No. 194,779

Term of patent 14 years

Int. Cl. D28—03

U.S. Cl. D86—10 C

FIG. 1 is a perspective view of a nail care tool embodying my new design;

FIG. 2 is an end view taken along line 2—2 of FIG. 1;

FIG. 3 is an end view taken along line 3—3 of FIG. 1;

FIG. 4 is a top plan view;

FIG. 5 is a bottom plan view; and

FIG. 6 is a side view taken along line 6—6 of FIG. 4.

I claim:

The ornamental design for a nail care tool, as shown.
